G. P. Gaefel

UNITED STATES PATENT OFFICE

HUBERT DALTON, OF STAMFORD, CONNECTICUT

THREADLESS NUT OR COLLAR

Application filed February 10, 1928. Serial No. 253,332.

This invention relates to a threadless nut or collar, and has for its primary object and purpose to provide means carried by the nut or collar whereby the same may be very easily, quickly and securely attached to a shaft or bolt, and also removed therefrom when necessary by the operation of a single retaining element which can be readily effected without necessitating the use of a tool or implement of any kind.

More particularly, my invention has for its essential object and purpose to provide a simple and novel form of spring locking member carried by the nut for cooperation with the walls of a groove in the bolt or shaft, and which member is so constructed that it can be easily actuated by the fingers of the hand and disengaged from said groove to permit of the axial movement of the nut to or from its applied position.

With the above and other objects in view, the invention consists in the improved threadless nut or collar, and in the form, construction and relative arrangement of the several parts thereof as will be herein-after more fully described, illustrated in the accompanying drawing, and subsequently incorporated in the subjoined claims.

In the drawing, wherein I have illustrated one simple and practical embodiment of the invention, and in which similar reference characters designate corresponding parts throughout the several views,—

Figure 1 is an end elevation partly in section showing the retaining member in full lines in its locking position and in dotted lines in the released position, the section being indicated by the line 1—1 in Fig. 2, and

Figure 2 is a bottom plan view of the device as seen in Fig. 1, a part of the nut being shown in section.

Referring in detail to the drawing, 5 indicates a shaft or rod having an annular groove 6 in one end thereof.

The nut or collar 7 is formed with an external annular groove 8 and in line with this groove, the nut 7 at one side thereof is provided with a slot 9 opening through the inner face of the nut.

The retaining member consists of a length of resilient wire having one end portion thereof bent or curved as at 10 and seated in the groove 8 at a point which is substantially diametrically opposite to the slot 9. 55 From this curved end portion, the wire is extended outwardly from the base of the groove 8 at a slight inclination as indicated at 11, and is then laterally extended and formed with the bend 12. From this bend 60 a long straight section 13 of the wire extends through the slot 9 and normally lies in intersecting relation to the inner longitudinal face of the nut. The other extremity of the wire projects laterally beyond the side of 65 the nut and is bent to form the terminal loop 14.

In the operation and use of the device as above described, in applying the nut to the end of the shaft or bolt, the thumb is placed 70 upon the surface of the nut between the bend 12 and the terminal loop 14 of the retaining member with which the first two fingers of the hand are respectively engaged and sufficient pressure is exerted against the terminal 75 loop 14 to position the straight portion 13 of the retaining member outwardly beyond the inner face of the nut 7. The nut may then be passed over the end of the shaft, and upon the release of pressure against the terminal 80 loop 14 of the wire retaining member, the part 13 thereof will snap into the groove 6 in the surface of the shaft, thereby securely locking the nut or collar against an axial movement relative to the shaft though permitting of its turning movement thereon.

When it is desired to remove the nut or collar, this may be readily accomplished by simply applying the finger and thumb of the hand as above explained and forcing the end 90 loop 14 of the wire retaining member outwardly to substantially the dotted line 11 of Fig. 1 of the drawings so that the nut can then be withdrawn longitudinally from the end of the shaft. It is thus seen that by the use of a retaining member of this form, the nut can be very easily and quickly applied or removed without the use of a tool of any kind, and also by eliminating the usual threads, the possibility of the nut becoming immov- 100

ably locked to the shaft by reason of mutilation of the threads will be obviated, also the necessity of rethreading is avoided by means of the present invention.

From the foregoing description, considered in connection with the accompanying drawing, the construction and several advantages of the device will be readily understood. I have found the particular form and construction of the retaining member as herein shown and described to be very advantageous in practical use, but it will nevertheless be understood that this retaining member both as to the construction thereof and the manner of its assemblage with the nut might be embodied in various other alternative forms. It is therefore, to be understood that I reserve the privilege of resorting to all such legitimate changes in the various details of the device as may be fairly considered within the spirit and scope of the invention as claimed.

I claim:

1. In combination with a shaft having a circumferential groove in the face thereof, a collar for said shaft having a transverse slot in one side extending entirely through the wall thereof, and a retaining member for said collar consisting of a length of resilient wire held at one of its ends in fixed relation to the collar and having an intermediate bend therein extending laterally from one side of the collar, and a substantially straight portion extending through said slot inwardly of the inner face of the collar and terminating in a loop projecting laterally from the opposite side of the collar, said straight portion of the retaining wire adapted for engagement in the groove in said shaft and said portion of the wire adapted to be sprung outwardly by pressure against said terminal loop to permit of the axial movement of the collar relative to said shaft.

2. In combination with a shaft having a circumferential groove in the face thereof, a collar having an external annular groove and a slot in line with said groove extending through the wall of the collar at one side thereof, a retaining member for said collar consisting of a single length of resilient wire having a curved end portion seated in the groove of said collar in fixed relation to the wall thereof and bent to provide a lateral loop extension from said fixed end portion and a straight relatively yieldable portion extending through said slot in the collar and normally intersecting the inner face of said collar, said latter portion of the wire projecting beyond one side of the nut and terminating in a finger engaging loop whereby pressure may be applied to spring said straight portion of the wire outwardly beyond the inner face of the nut and permit the collar to be moved longitudinally relative to the shaft, said straight portion of the wire re-

taining member adapted to normally seat in the groove in the shaft to thereby lock the collar against axial movement while permitting of its rotation relative to the shaft.

3. A collar having a transverse slot in one side extending entirely through the wall thereof, and a retaining member for said collar consisting of a length of resilient wire permanently attached at one of its ends to the collar and having a part at all times positioned within said transverse slot and extending therethrough for engagement with a circumferential groove in a shaft to retain the collar thereon and said wire at the opposite ends of said part thereof and externally of said slot being formed into finger engaging loops whereby said part of the wire may be sprung from its normal position out of the shaft groove to permit of the removal of the collar.

In testimony that I claim the foregoing as my invention, I have signed my name hereto.

HUBERT DALTON.
